BENCH

Ralph Mondragon, Taos, N. Mex.
(P.O. Box 199, Ranches of Taos, N. Mex. 87571)

Filed Feb. 27, 1970, Ser. No. 21,657

Term of patent 14 years

Int. Cl. D6—01

U.S. Cl. D15—11

FIG. 1 is a side elevational view of a bench showing my design;

FIG. 2 is a top view of FIG. 1;

FIG. 3 is a front side view of FIG. 1; and

FIG. 4 is a back side view of FIG. 1.

The side of the bench not shown is a mirror image of the side shown.

I claim:

The ornamental design for a bench, as shown and described.
